John R. Shepard

Charles J. Berg, Inventor

UNITED STATES PATENT OFFICE.

CHARLES J. BERG, OF DUHRING, PENNSYLVANIA.

KETTLE-LIFTER.

SPECIFICATION forming part of Letters Patent No. 630,317, dated August 8, 1899.

Application filed May 10, 1899. Serial No. 716,287. (No model.)

To all whom it may concern:

Be it known that I, CHARLES J. BERG, a citizen of the United States, residing at Duhring, in the county of Forest and State of Pennsylvania, have invented a new and useful Kettle-Lifter, of which the following is a specification.

This invention relates to means for preventing tea-kettles and other culinary vessels from becoming dry, and thereby damaged by the heat of a stove, and has for its object to provide a device which will automatically remove the tea-kettle or other vessel from the stove when the water has been reduced to a predetermined quantity either by use or evaporation and prior to the time when the vessel would become entirely dry.

To this end the present invention consists in the combination and arrangement of parts, as will be hereinafter more fully described, shown in the accompanying drawings, and particularly pointed out in the appended claims.

In the drawings, Figure 1 is a front elevation of the device shown in connection with a stove and applied in operative position to a tea-kettle. Fig. 2 is a side elevation thereof, showing the position of the device after the tea-kettle has been removed from the stove. Fig. 3 is a detail perspective view of the swinging arm of the device. Fig. 4 is a similar view of the fixed arm thereof.

Corresponding parts are designated by like reference characters in all the figures of the drawings.

Referring to the accompanying drawings, 1 designates a stove of common or ordinary form, and 2 a tea-kettle carried upon the top of the stove, these parts being shown to more fully illustrate the application and operation of the present device.

In carrying out my invention I employ a base 3, fastened to the floor adjacent to one side of the stove and near the back thereof. Fitted to this base is an upright standard 4, extending a suitable distance above the top of the stove and provided intermediate of its ends with a relatively-fixed arm or member 5 and a laterally-swinging member 6, located above the fixed member.

By reference to Fig. 4 it will be seen that the fixed member comprises a hollow or tubular arm provided near one end with a verti-

cally-disposed transverse opening 7, adapted to slidably receive the standard and held thereon at any vertically-adjusted position 55 by means of a set-screw 8, communicating with the opening 7 and adapted to bear against the standard. Inclined upwardly from the outer end of the fixed member is an arm 9, provided with a plurality of openings 10 and 60 carrying at its upper end a ring or collar 11, alined with the opening 7 in the inner end of the fixed member and adapted to receive the standard, so as to brace the member thereupon. The upper inner end of the inclined 65 arm is braced by means of a suitable arm 12, which extends upward from the inner end of the member.

Slidable longitudinally within the hollow arm 5 is a rod 13, carrying at its outer end a 70 flat plate 14, forming a table or platform, the latter being connected to the rod by means of a thumb-screw 15, passing loosely through the rod and entering a threaded opening formed centrally in the plate. The rod is 75 adapted to be adjusted toward and away from the standard, and it may be held at any adjusted point by means of a set-screw 16, carried by the hollow arm 5, near the outer end thereof, and adapted to engage the side of 80 the rod.

As best shown in Fig. 3 of the drawings, the swinging member comprises a hollow arm having at one end a vertically-disposed transverse opening 17, adapted to loosely receive the 85 standard 4, so that the member may be adjusted vertically and swung laterally thereon. Pendent from the outer end of the member and inclined toward the standard 4 is an arm 18, provided with a plurality of openings 19 90 and carrying at its lower end a ring or collar 20, alined vertically with the opening 17 and adapted to loosely receive the standard, whereby the member is effectively braced. The ring end of the arm 18 is connected to the 95 member by means of a pendent brace 21. A rod 22, having at its outer end a hook 23, is slidably mounted within the hollow arm 6 and is adapted to be held at any adjusted position therein by means of a suitable set-screw 24, 100 carried by the arm at or near its outer end. Located between the fixed and swinging members is a sleeve 25, slidable upon the standard and adapted to be adjustably held

thereon by means of a set-screw 26. The purpose of this sleeve is to form an adjustable support or stop for the swinging member, whereby the latter may be adjusted toward 5 or away from the fixed member and yet permit of the swinging movement of the member.

Pendent from the hook 23 of the swinging member is a coiled spring 27, provided at its lower end with a suitable hook 28 and at its 10 upper end with a short length of chain 29, so that any of the links may be engaged with the hook 23, whereby the hook 28 may be adjusted vertically with relation to the table or platform 14. The members 4 and 5 are entirely 15 independent of each other, but are adjustably connected together by means of a coiled spring 30, having its opposite ends hooked into the desired openings in the inclined braces 9 and 18, respectively.

20 In the application of the device as shown in Figs. 1 and 2 the fixed member is adjusted so that the table or platform 14 is on a level with the top of the stove. The rods 13 and 22, respectively, are adjusted so that the spring 25 27 may hang directly over the center of the table or platform 14, and the swinging arm is then turned or swung over the stove and the hook 28 engaged with the handle of the tea-kettle 2. It will be understood that when 30 the swinging arm is thus turned to one side a tension is placed upon the coiled spring 30, which has a normal tendency to return the swinging member to its normal position parallel with the fixed member; but this is prevented by reason of the combined weight of 35 the tea-kettle and the water contained therein. However, when the water has been reduced to a predetermined quantity either by reason of evaporation or use the combined 40 weight of the kettle and the water is also reduced below a predetermined weight, and when this point is reached the tension of the spring 30 is sufficient to return the swinging member to its original position, thereby automatically 45 removing the kettle from the stove and placing the same upon the platform 14.

By means of the sleeve 25 the swinging member may be adjusted with relation to the fixed 50 member, as will be understood, for the purpose of accommodating the spring 27 to kettles of different sizes, and the spring 30 is adapted to be connected with any of the openings provided in the inclined braces 11 and 20 for 55 the purpose of adjusting the throw or movement of the swinging member.

The present invention provides a simple and practical device which may be readily applied in position without altering or changing the 60 construction or form of a stove, and will automatically and effectively remove the kettle or other vessel from the stove, so as to prevent damage to the kettle by reason of the same becoming dry.

65 Changes in the form, proportion, size, and the minor details of construction within the scope of the appended claims may be resorted

to without departing from the spirit or sacrificing any of the advantages of this invention.

What I claim is—

1. A device of the character described, comprising a standard or support, a fixed member carried by the standard and provided with a table or platform, a swinging member mounted upon the standard and adapted to be connected with a kettle or other vessel located upon the top of a stove, and means whereby the swinging member is adapted to be operated to remove the kettle from the stove and onto the table or platform carried by the fixed member, substantially as shown and described. 70

2. A device of the character described, comprising a supporting-standard, a relatively-fixed member adjustable upon the standard 85 and provided with a table or platform, a swinging member located above the fixed member and adjustable upon the standard, and a spring operatively connecting the two members together, the swinging member being 90 adapted to be moved transversely of the fixed member and connected with a tea-kettle or the like located upon the top of a stove, whereby the spring is adapted to turn the swinging member to its normal position after the water 95 in the kettle has been reduced to a predetermined quantity, substantially in the manner shown and set forth.

3. A device of the character described, comprising an upright standard, a relatively-fixed 100 member carried by the standard, a table or platform carried by the member and adjustable toward and away from the standard, a laterally-swinging member carried by the standard and provided with a longitudinally- 105 adjustable rod having a hook, a coiled spring pendent from the hook, and a spring operatively connecting the two members together, substantially as shown and described.

4. A device of the character described, comprising an upright standard, a relatively-fixed member carried by the standard and provided with a table or platform and an upwardly-inclined arm having a plurality of openings, a 115 laterally-swinging member carried by the standard and located above the fixed member and having a downwardly-inclined arm provided with a plurality of openings, and a coiled spring adapted to have its opposite ends connected with any of the openings in the respective inclined arms, the swinging arm being adapted to be moved to a position transversely of the fixed member and connected to a tea-kettle or the like located upon the top of a stove, whereby the coiled spring is adapted 120 to return the swinging member to its original position, in the manner substantially as shown and described.

5. A device of the character described, comprising an upright standard, a relatively-fixed 130 member having a vertical opening formed through one end and adapted to receive the standard, a platform or table at the outer end of the member and an upright brace carrying

- a ring or collar alined with the opening provided in the member and adapted to receive the standard, whereby the member is braced upon the latter, a laterally-swinging member having an opening provided through its inner end, whereby said member is mounted upon the standard, and a pendent brace carrying a ring or collar alined with the opening in the member and adapted to receive the standard, 5 whereby the member is braced thereupon, said swinging member being adapted to be moved transversely of the fixed member and connected with the tea-kettle or the like, located upon the top of a stove and means operatively connecting the two members together, whereby the movable member is adapted to be returned to its original position, in the manner substantially as shown and described.
- 20 6. A device of the character described, comprising a standard, a relatively-fixed member carried by the standard and provided with a platform or table, a laterally-swinging member located above the fixed member and loosely 25 slidable upon the standard, a vertically-adjustable collar or sleeve provided upon the standard, located between the two members and adapted to adjustably support the swinging member, the latter being adapted to be 30 swung to one side and connected with a tea-kettle or the like, and means operatively connecting the two members together, whereby the swinging member is adapted to be returned to its normal position, substantially in 35 the manner described.
7. In a device of the character described,
- the combination with a standard, of a relatively-fixed member, consisting of a hollow arm having a vertical opening provided through one end, whereby the arm is mounted upon the standard, a set-screw communicating with said opening and adapted to engage the standard, a rod slidable longitudinally within the arm, a set-screw carried by the latter and adapted to adjustably hold the arm, 40 a plate connected to the outer end of the rod and adapted to provide a table or platform, a swinging member comprising a hollow arm having a vertical opening at one end whereby the arm is loosely mounted upon the standard, 45 a rod slidable longitudinally within the hollow arm and provided at its outer end with a hook, a set-screw carried by the arm and adapted to adjustably hold the rod, a coiled spring pendent from the hook, and a coiled 50 spring connecting the relatively-fixed member with the swinging member, the latter member being adapted to be swung to one side, and the pendent spring connected to a tea-kettle or the like located upon the top of 55 a stove, whereby the spring connecting the members is adapted to return the swinging member to its original position, in the manner and for the purpose substantially as shown and described.
- 60 In testimony that I claim the foregoing as my own I have hereto affixed my signature in the presence of two witnesses.
- CHARLES J. BERG.
